CLAIM

The ornamental design for a modal window for a computer display screen, as shown and described.

DESCRIPTION

FIG. 1 is a front view of a modal window for a computer display screen;
FIG. 2 is a front view of a second embodiment thereof;
FIG. 3 is a front view of a third embodiment thereof;
FIG. 4 is a front view of a fourth embodiment thereof;
FIG. 5 is a front view of a fifth embodiment thereof;
FIG. 6 is a front view of a sixth embodiment thereof;
FIG. 7 is a front view of a seventh embodiment thereof;
FIG. 8 is a front view of an eighth embodiment thereof;
FIG. 9 is a front view of a ninth embodiment thereof;
FIG. 10 is a front view of a tenth embodiment thereof;
FIG. 11 is a front view of an eleventh embodiment thereof;
and,
FIG. 12 is a front view of a twelfth embodiment thereof;
